AUTOMATIC GATE DEVICE

George R. Madden, Appleton, Ark.

Application September 22, 1958, Serial No. 762,388

4 Claims. (Cl. 39—22)

This invention relates to gate mechanisms, and it particularly relates to automatically actuated gate mechanisms.

There are various types of gate mechanisms of the automatic type now in use. Although some varieties of these gate devices are mechanically operated, the more popular type are those which are electrically operated as by means of a photoelectric cell or the like. These electrically operated gate mechanisms are, however, quite expensive to make and maintain and are subject to wiring defects and the like. Nevertheless, they have been generally preferable because of the relative complexity of prior mechanical gate devices and because of their general inefficiency and difficulty of maintenance.

It is one object to overcome the above and other disadvantages by providing a mechanically-operated gate device which is relatively simple in construction and which does not become easily subject to disrepair.

Another object of the present invention is to provide a mechanically-operated gate device which can be easily and cheaply installed.

Other objects of the present invention are to provide an improved automatic gate device, of the character described, that is easily and economically produced, which is sturdy in construction, and which is highly efficient in operation.

With the above and related objects in view, this invention consists in the details of construction and combination of parts, as will be more fully understood from the following description, when read in conjunction with the accompanying drawings in which:

Fig. 1 is a front elevational view of a gate device embodying the present invention.

Fig. 2 is a top plan view taken on line 2—2 of Fig. 1.

Fig. 3 is a sectional view taken on line 3—3 of Fig. 1.

Fig. 4 is a sectional view taken on line 4—4 of Fig. 2.

Fig. 5 is a sectional view taken on line 5—5 of Fig. 4.

Referring in greater detail to the drawings wherein similar reference characters refer to similar parts, there is shown a gate device, generally designated 10, comprising a pair of gates 12 formed of a generally rectangular frame enclosing a wire mesh closure material 13.

Each gate 12 is provided at its outer edge with a vertically-spaced pair of gate supporting rods 14. Each rod 14 extends through a pair of aligned spiral cam slots 16 in opposite sides of a hollow post 18, one such post 18 being provided adjacent the outer edge of each gate 12, the supporting rods 14 thus acting as a cam means in the cam slots 16. These posts 18 are each supported on the upper surface of a hollow cross base 20 and open down into the cross base 20 (as best shown in Fig. 4). The rods 14 each also extend, between the aligned spiral cam slots 16, through a transverse bore 22 in a vertical pintle 24 longitudinally movable in the corresponding post 18.

Each pintle 24 rests on the free end of a link or lever 26 which is pivoted intermediate its length to a pivot pin or rod 28. There are two such levers 26 extending in op-

posite, inclined directions (as best shown in Fig. 4); each lever 26 being hingedly attached, as at 30, to the corresponding end of a vertically-movable, floating treadle platform 32.

- 5 The treadle platform 32 is provided with a pair of oppositely-disposed treadle supporting posts 34 which underlie and support a pair of treads 36 each of which includes side flanges 38 and an upper wear surface 40. The side flanges 38 are adapted to extend into slots 42 in the top wall of the base 20. The treads 36 are elongated and are arranged in parallelism with each other, extending for a substantial distance on both sides of the gates 12, but extend a longer distance on the opening side 41 of gates 12, and are pivoted at 37 at their ends 10 to the sides of elongated base boxes 39, which base boxes extend to opposite sides from cross base 20.

In order to prevent the gates 12 from swinging beyond their closed positions, a pair of stops 44 are positioned on the cross base 20, each being adjacent the inner edge of 20 each gate.

In the operation of the above-described device, when a person steps on either of the treads 36 or a car or other vehicle of a weight exceeding a predetermined level is driven onto the treads from either side of the gates 12, 25 the platform 32 is depressed at one end if one treadle is depressed, or both ends of both treadles are depressed. Upon being depressed, the platform 32 acts to pivot the lever or levers 26 around their respective pivot pins 28. These levers 26 then push up on their respective pintles 30 24. As the pintles 24 move up, they move the gate supporting rods 14 through the aligned spiral cam slots 16 which pivots the gates 12 outwardly into the open position. Upon the person or vehicle leaving the treadles 36, the pintles 24 move down under the force of gravity 35 acting on the gate or gates 12, moving the rods 14 in the opposite direction in their spiral cam slots 16 to close the gates 12 and moving the platform 32 upwardly.

Although this invention has been described in considerable detail, such description is intended as being illustrative rather than limiting, since the invention may be variously embodied, and the scope of the invention is to be determined as claimed.

Having thus set forth and disclosed the nature of this invention, what is claimed is:

- 45 1. An automatically openable and closeable gate device comprising a swinging gate, said gate having an outer edge about which the gate is swung, said gate having outwardly extending gate supporting cam rods on its outer edge, a hollow support post for said gate adjacent its outer edge, said support post having oppositely aligned spiral cam slots through which said cam rods extend, a pintle extending vertically through said hollow post, each said cam rods extending through transverse bores in said pintle between said oppositely aligned cam slots, a longitudinal treadle member for said gate extending a substantial distance at right angles to both sides of the closed position of said gate, and lever means extending from beneath said pintle to beneath said treadle means and pivoted intermediate said pintle and treadle means where- 50 by when a weight surpassing a predetermined value is placed on or moves over said treadle means, said gate is opened and maintained open only while the weight remains thereon and is automatically closed when the weight is removed from the treadle means.
- 55 2. An automatically openable and closeable gate device comprising a pair of swinging gates, each gate having an inner edge adjacent each other when in closed position and an outer edge about which the gate is swung, each gate having outwardly extending gate supporting cam rods on its outer edge, a hollow support post for each gate adjacent its outer edge, each support post having oppo- 60 sitely aligned spiral cam slots through which said cam rods
- 65 70

extend, a pintle extending vertically through each hollow post, each said cam rods extending through transverse bores in said pintles between said oppositely aligned cam slots, a longitudinal treadle member for each gate extending a substantial distance at right angles to both sides of the closed position of said gates, and lever means extending from beneath said pintles to beneath said treadle means and pivoted intermediate said pintles and treadle means whereby when a weight surpassing a predetermined value is placed on or moves over either treadle means, its adjacent gate is opened and maintained open only while either weight remains thereon and is automatically closed when the weight is removed from the treadle means.

3. The device of claim 2, and a hollow base extending between said hollow gate posts beneath said treadle means, said lever means extending in said hollow base.

4. The device of claim 3, and a floating platform linking said lever means between said treadle means whereby a weight on either treadle means opens both said gates.
